UNITED STATES PATENT OFFICE.

EDWARD ALFRED GRAHAM, OF BROCKLEY, LONDON, ENGLAND.

GRAMOPHONE AND LIKE MACHINE.

1,401,069.

Specification of Letters Patent. Patented Dec. 20, 1921.

Application filed March 22, 1921. Serial No. 454,420.

To all whom it may concern:

Be it known that I, EDWARD ALFRED GRAHAM, a subject of the King of Great Britain and Ireland, residing at Brockley, 5 in the county of London, England, have invented Improvements in or Relating to Gramophones and like Machines, of which the following is a specification—

The object of the present invention is to 10 provide improved means for stopping and starting gramophones, phonographs, and like machines.

According to the invention, the motor driven table or record carrying element is 15 arrested by means of a brake pad or the like brought into contact with a brake disk or equivalent device in connection with the motor of the machine.

In a machine embodying the invention, 20 a tone-arm carrying a sound reproducer and mounted to turn about a vertical axis, is provided with a trip arm or projection which is adapted at a position intermediate of the range of angular movement of the tone-arm, 25 to cause a brake lever to release the motor and allow the same to start, and toward each limit of its angular movement, to move latch mechanism and so permit the brake lever to act to stop the motor.

30 The brake lever, which is adapted to be depressed by the trip arm upon the tone-arm, carries a resilient pad or like member which, until the lever is depressed comes into contact with a disk or similar device connected 35 to the governor spindle or other part of the motor thereby arresting the drive of the machine.

In order that the nature of the said invention may be fully understood, reference will 40 now be made to the accompanying drawings wherein Figure 1 shows in plan view, and more or less diagrammatically, part of a gramophone or like machine with one construction of starting and stopping apparatus according to the invention and Fig. 2 is a perspective view showing parts of the said apparatus in a different position and to a larger scale.

Fig. 3 shows, more or less diagrammatically, part of a gramophone or like machine provided with another construction of starting and stopping apparatus according to the invention, the brake lever being shown in its operative position. Fig. 4 is a similar 55 view to Fig. 3 with the brake lever in the inoperative position. Fig. 5 is a plan of

the apparatus as shown in Fig. 4. Fig. 6 is a vertical section corresponding to the line VI—VI of Fig. 5. Fig. 7 shows a socket in side elevation. Fig. 8 shows a modified 60 form of socket.

In the example shown in Figs. 1 and 2, the tone-arm 1 provided with a sound reproducer at its free end, carries an adjustable trip arm 2, which, in the position shown 65 in Fig. 2, engages the cam-like end 3^c of a brake lever 3, 3^a, pivoted at 3^b, to the stationary top or table A of the machine, depressing the arm 3 of the lever and elevating the other arm 3^a and a brake pad 4 at the 70 end thereof out of contact with the disk 5 of the motor governor 5^a. The machine can now run but any further movement of the tone-arm outward into the position shown in Fig. 1, causes the trip arm 2 to engage 75 with and press back one arm 6 of a stop lever 6—7 which is pivoted at 6^{*} on the brake lever 3, 3^a. The other arm 7 of this stop lever is thereby caused to bear against a latch 8, pivoted at 8^a, so as to withdraw a 80 detent 9 thereon from the arm 3 of the brake lever 3, 3^a which is then tilted upward, under the action of a spring 10 beneath it, so as to depress the other arm 3^a of the lever and force the brake pad 4 into contact with 85 disk 5 and stop the machine and hold the machine stationary all the time the said reproducer and associated tone-arm are moved away from the record B (Fig. 1). 11 is a spring connected to the arm 6 of the lever 90 6—7 and to the latch 8 and arranged to urge the latch 8 toward the brake lever 3, 3^a. Moving the tone-arm inward to start playing, causes the trip arm 2, as soon as it reaches the first described position 95 (Fig. 2) to depress the adjacent end of the levers 3, 3^a by acting on its cam like end 3^c, and enable the motor to start after which the arm 3 of the lever is maintained in the depressed position by the detent 9 under the action of the spring 11 until the tone-arm 1, in playing the record, is carried into contact 100 with a stop lever 12. This lever being mounted on the pivot pin 8^a of latch 8 and frictionally engaging the latch, will, when 105 engaged by the trip arm 2, displace the latch 8 and withdraw the detent 9 from the arm 3 of the brake lever thus allowing the latter to move, under the action of its spring 10, and stop the machine automatically at the 110 end of the record. The position of the frictionally held stop lever 12 can be adjusted

by hand to enable it to be operated by hand at the required time to suit the particular sound record B being used.

The first mentioned latch operating member namely 6—7 may be replaced by a member mounted independently of the brake lever 3—3^a and be adapted to be positively actuated in opposite directions by the trip device when the tone arm is moved into 10 and from its outer inoperative position, and when moved in one direction, will directly move the brake lever into its inoperative position and release the latch so that it can move into a position to hold the lever in the 15 inoperative position, and when moved in the opposite direction will move away from the brake lever and force the latch away from the said lever so as to leave the latter quite free from both the said lever and the latch. 20 To this end, the trip device may consist of a pin extending horizontally from a tone arm and mounted to turn in a stationary socket and the said latch operating member be in the form of a lever mounted to 25 turn in a vertical plane about a pivot carried by the socket. The second latch operating member and the latch to which it is adjustably and frictionally held may be replaced by members mounted to slide horizontally 30 in a vertical plane adjacent to a bearing or abutment on the said socket and be urged in a direction toward the brake lever by a spring connected to the latch member and to a fixed point, which may be 35 on the said socket.

Figs. 3 to 7 inclusive, show starting and stopping apparatus thus modified. In this example, 3, 3^a is the brake lever, 8 the latch carrying a detent 9^a adapted to hold the 40 said lever in its inoperative position, 6^a—7^a the first latch operating member, 12^a the second latch operating member and 2^a the trip device carried by the tone arm 1. The latter is swiveled in a socket 14 which is 45 fixed in a tubular holder 15 (Fig. 6) secured to the stationary table 16 of the machine.

The brake lever 3, 3^a is pivoted to the stationary table A at 17 and is provided with a coiled spring 18 adapted to raise its arm 3 and to depress its other arm 3^a and move a 50 brake shoe 4^a carried thereby into contact with the brake disk 5 connected to the governor 5^a of the motor used to rotate the record carrying turntable, which is not 55 shown, but will as usual be above the stationary table A. The brake shoe may conveniently be carried by a vertical pin 19 fixed to a longitudinally adjustable end portion 3^d of the brake lever 3—3^a and be fitted 60 with a sleeve 20 where it extends through a hole 16^a in the table A.

The latch 8^a and its operating member 12^a are slotted at 21 and 22 respectively for the reception of screws 23 by which they 65 are connected to an abutment 24 (Fig. 5)

on the fixed socket 14, the two parts 8^a and 12^a being held in frictional connection with each other and with the abutment 24 and the heads of the screws 23 by an interposed blade spring 25. The latch operating member 12^a 70 is provided with an upward extension 12^b arranged in the path of the trip device which is constituted by a pin 2^a extending laterally and horizontally from the tone arm 1. The member 12^a is endwise adjustable 75 on the latch 8^a against the action of the spring 25, to vary the position of the extension 12^b to suit the length of a sound record to be played. 26 is a spring connected at one end to the latch 8^a and at 80 the other end to the socket 14 and adapted to urge the latch toward the adjacent raised end portion 3 of the brake lever 3—3^a. The detent 9^a carried by the latch 8^a and adjacent to the brake lever, is notched at 85 9^b to admit of its overlapping the end portion 3^c of the brake lever (see Fig. 4) when the same is depressed. The latch 8^a is provided with an inclined cam surface at 8^b.

The latch operating member 6^a—7^a 90 consists of a flat lever pivoted on a horizontal pin 27 fixed to an extension 28 of the socket 14, so that it can turn in a vertical plane. Its end 6^a is adapted to be directly moved in opposite directions by the trip device 95 2^a in order to cause its other end 7^a respectively to depress the adjacent arm 3 of the brake lever 3—3^a and to release such arm. The upper edge of the end 7^a of the said lever is arranged to work below the inclined 100 cam surface 8^b of the latch 8^a. The said lever is formed with a slot 6^b through which extends a motion limiting screw 29, and with a slot 6^c.

The tone arm 1 is connected by a ball and 105 socket joint 30 (Fig. 6) in known way to the socket 14 and is acted upon by a spring that tends normally to tilt the tone arm into a raised position, thus acting against the weight of the sound reproducer 31. 110 (Fig. 1.) The spring may, as shown in Figs. 5 and 6, conveniently be a coiled spring 32 carried by a pin 33 mounted in a bearing 34 forming part of a vertical T shaped member 35 fixed in a tubular portion 14^a of a 115 vertical diametrically arranged cross piece forming part of the socket 14. The two ends 32^a of the spring 32 act against the top of the bearing 34 while an intermediate looped portion 32^b of the spring bears 120 against the bottom edge of the tone arm 1 at its forward side. (Fig. 6.)

As will be seen, the arrangement is such that when the tone arm 1 is in its outer inoperative position shown in Fig. 3, the 125 latch 8^a will be held back out of engagement with the adjacent end portion 3^c of the brake lever 3—3^a by the raised end 7^a of the latch operating lever 6^a—7^a acting against the inclined cam surface 8^b of such latch 8, and 130

the brake lever 3—3^a will be in its operative position to stop the motor. When the tone arm is moved in the direction of the arrow in Fig. 5, for playing a record, the trip pin 2^a will operate the lever 6^a—7^a in a direction to cause its end 7^a to depress the adjacent end portion 8^a of the brake lever 3—3^a to release the motor and also to release the latch 8^a and enable the notched end of 5 detent 9^a of the latter to overlap the raised end portion 3^a of the lever and hold the lever in its inoperative position, whereupon the playing of a record can be commenced, and the tone arm thereby caused to move in the 10 direction mentioned. When the playing of the record is finished, the trip pin 2^a, by acting against the extension 12^b of the member 12^a, will draw back the latch 8^a from the 15 brake lever 3—3^a which will then be moved into its operative position under the action of its spring 18, to stop the motor and record carrying turntable and slightly raise the arm 7^a of latch operating lever 6^a—7^a. When the tone arm 1 is moved back into the 20 position shown in Fig. 3, the trip pin 2^a will slide over the end 6^a of the lever 6^a—7^a and act to raise the end 7^a so as to cause the latter, by acting against the inclined surface 8^b on the latch 8^a, to move back such latch into 25 its inoperative position, and will finally drop into the slot 6^c in the lever 6^a—7^a so as to hold the tone arm in its outer and inoperative position and leave the brake lever 3—3^a free from the latch 8^a and lever 6^a—7^a. The 30 swivel mounting of the tone arm permits the trip pin 2^a to rise over the forward side of the arm 6^a of the lever 7^a and fall into the slot 6^c therein.

A portion of the upper edge of the socket 35 14 may advantageously be shaped in the manner shown in Figs. 3, 4 and 7 to form a notch 36, having cam like end surfaces 36^a—36^b and supplementary notches 37 and 38 for the reception of the trip pin 2^a. The arrangement is such that when the tone arm 1 with attached sound reproducer is turned 40 into its outer inoperative position, shown in Fig. 3, the pin 2^a will ride up over the cam surface 36^a and act against the arm 6^a of the lever 6^a—7^a to raise the end 7^a of such lever as described and then enter the notch 45 37 and be held against the bottom thereof by the weight of the sound reproducer on the tone arm, the latter being thus held in a raised inoperative position, as for instance 50 during the changing of a sound record. When the tone arm is moved in the opposite direction, it will, by acting against one side of the notch 37 depress the end 7^a of the lever as hereinbefore described for the purpose set forth. When the tone arm is afterward being moved into its innermost position, the pin 2^a will ride up over the cam surface 36^b and enter the notch 38 against 55 the bottom of which it will firmly be held

by the weight of the sound reproducer with the tone arm in a raised and inoperative position suitable for the transport of the machine from place to place. The pin 2^a will be moved upward against the lower face of 70 the hook at 39 by the action of the coiled spring 32, when the sound reproducer is removed from the tone arm.

According to the modification shown in Fig. 8, the cam surfaces 36^a, 36^b, seats 37 75 and 38 and hook 39 are omitted and the socket 14 is formed with a recess of the shape shown at 40 for the trip pin 2^a to work in. In this case the latch operating lever 6^a—7^a is formed with a rounded projection as 80 shown at 6^d to admit of its being operated in one direction by the trip pin 2^a to depress the end 7^a of the said lever, and the tone arm instead of being mounted to swivel about a universal joint, as hereinbefore described, is 85 mounted to turn only about a vertical axis in the ordinary way and is provided, in known manner, with a jointed tube or goose neck to carry the sound reproducer.

What I claim is:—

1. In a gramophone or like machine, the combination with a movable device driven from the gramophone motor and an angularly movable tone arm, of a trip device carried by said tone arm, a spring controlled 95 brake lever adapted, when released, to arrest said movable device and motor, a latch member adapted when in its operative position to hold said lever in its inoperative position, and two latch operating members arranged to be actuated by the trip device when moved into its limiting angular positions with the tone arm, each latch operating member when so operated, acting to cause the latch member to release the said lever. 100

2. A gramophone or like machine having starting and stopping mechanism according to claim 1, wherein the latch member is normally urged toward the brake lever and one of the latch operating members is adapted, 110 when the trip device is being moved from its outer limiting position, to move the brake lever into its inoperative position and permit the latch member to hold it in that position.

3. A gramophone or like machine according to claim 1, wherein the latch operating member that is actuated by the trip device when nearing its inner angular limiting position, is adjustably connected to the latch 120 member.

4. In a gramophone or like machine, the combination with a movable device driven from the gramophone motor and an angularly movable tone arm, of a trip device 125 carried by the tone arm, a spring controlled brake lever adapted, when released, to engage said movable device and arrest the motor, a spring actuated latch member adapted to engage said brake lever when it is 130

the inoperative position and hold it in that position, a latch operating lever arranged to be actuated in opposite directions by said trip device when moving into and from its 5 outer angular limiting position and respectively to move the latch member into its inoperative position and release the brake lever and to move the brake lever into its inoperative and permit the latch member to 10 move into its operative position and hold the brake lever in its inoperative position, and a second latch operating member arranged to be actuated by the trip device when nearing its inner angular limiting position and to then withdraw the latch member 15 from the brake lever.

5. In a gramophone or like machine, the combination with a movable device driven from the gramophone motor and an angularly movable tone arm, of a trip device carried by said tone arm, a brake lever adapted, when released, to engage said movable device and arrest the motor, a vertical socket wherein the inner end of the tone arm can 20 turn, a latch member arranged to slide in a vertical plane against said socket and provided with a detent adapted to engage one end of said brake lever when depressed and to hold the lever in the inoperative position, 25 a latch operating lever mounted on said socket to turn in a vertical plane above the said end of the brake lever and adapted to be moved by the trip device, on the outward movement thereof, in a direction away from 30 said end of the brake lever and to disengage the detent therefrom and allow the brake lever to move into its operative position, and when caused to move in the opposite direction, upon movement of the trip device in 35 an inward direction, to depress said end of the brake lever and allow the detent to engage it and hold the brake lever in the inoperative position, and a second latch operating member adapted to be moved by the 40 trip device, when nearing its inner position, and to then move the latch member and detent into the inoperative position to release the brake lever.

6. In a gramophone or like machine, the 50 combination of a motor driven member, a brake lever adapted automatically, when released, to arrest said member and motor, a fixed socket, a tone arm angularly movable in said socket, a trip pin extending laterally 55 from said tone arm, a spring actuated latch member with detent adapted automatically to engage said end of the lever when depressed, a latch operating member connected to said latch member and adapted to be engaged by said trip pin when nearing the 60 inner end of its angular movement with the tone arm and to then withdraw the latch member and detent from the brake lever, a latch operating lever pivoted to said socket 65 so as to oscillate above said end of the brake

lever and to be operated by said trip pin when the same is moved into and from its outer limiting angular position, the outward movement of the pin causing the latch operating lever to release the brake lever and move the latch member and detent into their inoperative positions and the inward movement of the trip pin causing said latch operating lever to move the brake lever into the inoperative position and release the latch 75 member and detent and enable them to hold the brake lever in the inoperative position.

7. In a gramophone or like machine, the combination of a motor driven member, a brake lever adapted automatically, when released, to arrest said member and motor, a fixed socket, a tone arm angularly movable in said socket, a trip pin extending laterally from said tone arm, a latch with detent and latch operating member both in the form of 80 flat plates frictionally held together and mounted to slide on said socket and to be moved away from one end of the brake lever by the trip pin, and a latch operating lever pivoted to said socket above said end of the 85 brake lever and adapted to be turned in opposite direction by said trip pin, movement of said latch operating lever in one direction releasing the brake lever and moving the latch and detent into the inoperative 90 position and movement in the opposite direction moving the brake lever into its inoperative position and then allowing the latch and detent to move into their operative positions to hold the brake lever in the inoperative 95 position.

8. In a gramophone or like machine, the combination with a motor driven member, a brake lever adapted automatically, when released, to arrest said member and motor, a stationary socket, a tone arm swiveled in said socket, a spring acting in a direction on said tone arm, tending to lift its outer free end, said socket being formed at its upper edge with a recess having at each end thereof a cam surface and a supplementary notch with seat and above one of said notches and seats a hook, a trip pin arranged to travel in said recess and over the cam surfaces and into the notches, a spring actuated latch 105 member mounted to slide on said socket toward and from said brake lever and thereby to respectively hold and release said lever, a latch operating member adapted to be operated by the trip pin when nearing the 110 end of its inward angular movement, to withdraw the latch member from the brake lever and a slotted latch operating member pivoted to said socket and adapted to be operated by said trip pin when moving into 115 its outer angular limiting position, said pin then sliding over the adjacent cam surface and moving the pivoted latch operating member in one direction to move the latch member into its inoperative position and 120 125 130

permit the brake lever to move into its operative position, the pin then entering the slot in the said slotted lever and coming to rest on the seat at the bottom of the corresponding notch in the socket, the pin when moved in the opposite direction acting to move the slotted lever in the opposite direction to move the brake lever into its inoperative position and permit the latch member to move into its operative position to hold the brake lever in its inoperative position.

Signed at St. Andrews Works, Crofton Park, London, England, this third day of March 1921.

EDWARD ALFRED GRAHAM.
